UNITED STATES PATENT OFFICE.

HARRY VISSERING, OF KENILWORTH, ILLINOIS, ASSIGNOR TO THE OKADEE COMPANY, OF CHICAGO, ILLINOIS, A CORPORATION OF ILLINOIS.

LOCOMOTIVE-BOILER FRONT-END HINGE.

Application filed September 25, 1920. Serial No. 412,648.

To all whom it may concern:

Be it known that I, HARRY VISSERING, a citizen of the United States, and a resident of Kenilworth, Cook County, State of Illinois, have invented certain new and useful Improvements in Locomotive-Boiler Front-End Hinges, of which the following is a specification.

This invention relates to closure supports and particularly to a support for the type of closure used in the boiler of locomotives and commonly termed the front end as it is the plate for closing the forward end of the boiler.

Although this invention is illustrated and described in connection with the closure for the front end of a locomotive boiler, it is to be understood that the invention is capable of use in other relationships and with other types of construction.

This plate is large and extremely heavy and according to approved railway practice is secured to the boiler front by a great number of stud bolts and nuts circumferentially arranged adjacent the outer edge of the front plate. In order to make the joint between the boiler front and the front end plate absolutely tight, the nuts are turned down as closely as possible. When it is desired to remove the front end plate to reach the inside of the boiler, the nuts are removed and the front plate moved away from the boiler shell. This removal of the front plate is extremely difficult, as the front plate will stick to the stud bolts and to the boiler front, a natural result of the rusting effect and of the exposure of the parts to the elements. In replacing the front plate on the boiler, similar difficulties will be encountered particularly if any irregularities should have developed in the relative positioning of the stud bolts.

Still another difficulty encountered in the removal of this front plate is that its weight is such that a crane and tackle are found necessary to carry the weight of the plate as soon as it is moved away from the position in which it is supported by the boiler. This necessitates that the engine be moved to a spot where such crane and tackle are at hand.

The principal objects of this invention, therefore, are to provide an arrangement whereby the front end plate can be moved away from the boiler front without the ex-

penditure of time and effort hitherto found necessary; the provision of means for moving the front plate away from the boiler front by the application of force directly against the inside surface of the front plate and at a point within the confines of the plate; the provision of an improved arrangement for causing said plate to properly seat itself on the boiler front, when it is desired to replace the plate end in closing position; the provision of an improved structure in which the front plate can be moved to a position away from the boiler without at the same time moving the front plate from a position of support by the boiler; the provision of a novel mechanism which will permit the front plate to be moved outwardly away from the boiler front and out of direct contact therewith and which will then permit the front plate to be moved to the side so as to permit free access to the boiler interior while still retaining the front plate at all times in a position of support by the boiler; the provision of means for positioning this mechanism most advantageously from the standpoint of structure design and also so as to place the mechanism in a protected position and hidden from view; together with further and additional objects as will hereinafter appear.

In attaining the stated objects and certain additional benefits and advantages, I have provided a construction, wherein—

Figure 1 shows a front view (partly broken away) of the boiler front with the end closure plate attached in operative position;

Figure 2 shows a section through the mechanism for supporting the end closure plate from the boiler shell, and

Figure 3 shows a section taken at a right angle to that of Figure 2.

Looking first at Figure 1, it will be noted that the boiler, 10, shown is circular in cross section and that the end or closure plate, 11, for the front end of the boiler is secured to the boiler front by means of the circular row of stud bolts, 12, carried by the circular ring, 13, secured to the boiler, and passing through the corresponding opening on the front end plate, 11. Upon these stud bolts are threaded the nuts 14.

Supported from the inside wall of the boiler, 10, by means of the flanges 15, 16 and 110

17 is the main supporting bracket, 18, of substantial dimensions, which as shown is box-like in construction. Slidably mounted within and supported by the bracket, 18, is 5 the member, 19, which carries the front end closure plate 11. The member, 19, is guided so as to have a sliding movement back and forth on the bracket support, 18, parallel to the longitudinal axis of the boiler. It is 10 obvious, therefore, that as this member, 19, is reciprocated the closure plate, 11, will be moved with it either away from or towards its closure position on the boiler front. I have thus provided an arrangement for supporting the closure plate from the inside of 15 the boiler wall which is not only substantial in character, but which also permits of the front end plate being moved away from the boiler opening without moving the end plate 20 from its position of support by the boiler shell.

For imparting to the member, 19, the aforementioned reciprocation, the threaded member, 20, is mounted freely for rotation in 25 the supporting flanges, 15 and 21, said member, 20, being held against any bodily movement longitudinally by the abutment members, 22, fixedly carried by the member, 20, on each side of the flange, 15.

30 Threadedly engaging the screw, 20, is the nut, 23, held against rotation with the screw, 20, by depending part, 24, thereof engaging the sliding member, 19, between the side walls and the end flanges 25 and 26.

35 By this arrangement, when the screw 20 is rotated, the nut, 23, will be caused to travel thereon either backwardly or forwardly, depending upon the direction in which the screw is rotated. The nut, 23, will carry 40 with it the sliding member, 19, and will thus cause the end closure member, 11, to move either to or from its closing position.

The screw, 20, is provided with the squared end, 27, to receive a crank-handle 45 by which the screw, 20, can be manually rotated, and to admit this the front plate, 11, is provided with an opening through which the crank can be inserted, which opening is normally closed by the plug, 28. When it 50 is desired to rotate the screw, 20, the plug, 28, is removed and the crank is inserted through the opening into engagement with the squared end 27.

55 It will thus be seen that I have provided a support for the front end closure plate, and mechanism for positively moving said support and end plate both backwardly and forwardly, all located within the boiler interior, protected from blow and hidden from view.

60 Furthermore, by the use of the rotating screw the force manually used in rotating the crank is applied most advantageously to move the closing plate 11.

Mounted upon the sliding member, 19, is 65 the hinge pin, 29, upon which is pivotally

mounted the hinge members, 30, integral with the member 31 rigidly secured to the end plate, 11. Upon viewing Figure 2, it will be noticed that the hinge for the end closure plate, 11, is located at a substantial 70 distance inwardly from the edge, 32, of the plate, 11. When, therefore, the sliding member, 19, is moved outwardly a distance sufficient to permit the outer edge, 32, to clear the boiler at the time the end plate, 11, is turned about the hinge pin, 29, the end plate can be swung to one side. This procedure is assisted considerably by the fact that the hinge pin, 29, is placed inwardly of the outer edge of the plate 11. 75

To limit the extent to which the end closure plate, 11, can be swung to the side, the slide, 19, is provided with the flange, 33, which acts as an abutment stop for the end closure member, 11, as clearly shown in 80 dotted lines in Figure 2 of the drawings.

I have thus provided a structure in which the mechanism by which the closure member is mounted for bodily movement and for pivotal movement is hidden from 90 view and is given a substantial support from the inside of the boiler. I have furthermore provided a structure in which both parts of the hinge are movable together as a unit with the end closure element. I have further 95 provided a construction in which the mechanism used not only moves the end closure plate, 11, to unseat it but also moves it in the opposite direction to force it on its seat and one in which the force is applied to 100 the end plate in a straight line from a point inwardly of the plate.

Having thus described my invention and illustrated its use, what I claim as new and desire to secure by Letters Patent is— 105

1. In combination, a boiler having an opening thereto, a closure for said opening, and means for supporting said closure from said boiler, said means being movable to and from a position within the boiler. 110

2. In combination, a boiler having an opening thereto, a closure for said opening, and means for supporting said closure for movement from and to a closing position, said means being carried from the interior 115 of the boiler.

3. In combination, a boiler having an opening thereto, a closure for said opening, means positioned within the boiler for supporting said closure for movement from and to the boiler, and means operable from the exterior of the boiler for moving said closure from and to its closing position. 120

4. In combination, a boiler having an opening thereto, a closure therefor mounted for movement from and to the opening, and means operable against the inner surface of the closure for imparting movement thereto. 125

5. In combination, a boiler having an 130

opening, a closure for said opening, and means for supporting said closure for movement relatively to said boiler, including a member within the boiler and a second member 5 movably carried thereby, said second member carrying the closure.

6. In combination, a boiler having an opening, a closure for said opening, and means for supporting said closure for movement relatively to said boiler, including a member within the boiler and a second member movably carried thereby, said second member carrying the closure, said second member and said closure being connected for relative movement.

7. In combination, a boiler having an opening thereto, a closure for said opening, and means for supporting said closure for pivotal movement relatively thereto, said means being supported within the boiler.

8. In combination, a boiler having an opening thereto, a closure therefor and means for supporting said closure from said boiler for movement relatively thereto, said means comprising a member on the boiler and a member on the closure, both of said members being movable together relatively to the boiler.

9. In combination, a boiler, a closure thereto, and means for supporting said closure from said boiler for movement relatively thereto, said means including two bodily movable members.

10. In combination, a boiler, a closure thereto, and means for supporting said closure from said boiler for movement relatively thereto, said means including two members both bodily movable relatively to the boiler and movable relatively one to the other.

11. In combination, a boiler having an opening, a closure for said opening, a bracket carried by and within the boiler, a member slidably carried on said bracket, and a hinge connection between said closure and said boiler.

12. In combination, a boiler having an opening, a closure for said opening, a bracket support carried by and within the boiler, a member slidably carried on said bracket, a hinge connection between said closure and said boiler, and means located within the boiler and operable from the exterior thereof for producing relative movement between said bracket support and said 50 slideable member.

13. In combination, a boiler, an opening thereto, a closure for said opening, means for supporting said closure comprising a bracket supported from the boiler interior and located within the boiler, and a member slidably carried on said bracket, and a hinge carried by said member, one part of the hinge being fixed to said member and the other fixed to said closure 65 whereby the closure is mounted for bodily movement to and from the boiler, and also for swinging movement relatively thereto.

14. In combination, a boiler, and opening thereto, a closure for said opening, 70 means for supporting said closure comprising a bracket supported from the boiler interior and located within the boiler, a member slidably carried on said bracket, and a hinge carried by said member, one part of 75 the hinge being fixed to said member and the other fixed to said closure whereby the closure is mounted for bodily movement to and from the boiler, and also for swinging movement relatively thereto, and means 80 for moving said slideable member along the bracket, comprising a member mounted for rotation in said bracket and a member in engagement therewith and in non-rotatable engagement with the slideable member.

In testimony whereof I have hereunto signed my name in the presence of the two subscribed witnesses.

HARRY VISSERING.
